DRILLING APPARATUS

Eugene Whinnen, Republic, Mich., assignor to
 Sullivan Machinery Company, a corporation of
 Massachusetts

Application January 5, 1932, Serial No. 584,829

13 Claims. (Cl. 254—139)

This invention relates to drilling apparatus and more particularly to improvements in controlling mechanism for the rod line of a drilling apparatus of the oil and gas well type.

5 An object of this invention is to provide improved rod line controlling mechanism for an oil and gas well drilling apparatus. Another object is to provide an improved mechanism for controlling the rod line in the drill hole 10 when relatively high subterranean pressure is encountered during the drilling operation. A further object is to provide an improved rod line snubbing device for moving the rod line into the drill hole and withdrawing the rod line 15 from the hole while subjected to relatively high subterranean pressure. Yet another object is to provide an improved rod line snubbing device having improved rod gripping means and improved means for operating the gripping means 20 from the derrick floor. These and other uses and advantages of this invention will, however, hereinafter more fully appear.

In the accompanying drawings there is shown for purposes of illustration one form which the 25 invention may assume in practice.

In these drawings:

Fig. 1 is an elevational view showing the 11-
 30 illustrative embodiment of the improved rod line
 snubbing device and its associated mechanism.

Fig. 2 is an enlarged side elevational view
 35 of the improved rod line snubbing device.

Fig. 3 is a bottom plan view of the snubbing
 device shown in Fig. 2.

Fig. 4 is a vertical sectional view taken sub-
 35 stantially on line 4—4 of Fig. 3.

Fig. 5 is a detail vertical sectional view taken
 40 substantially on line 5—5 of Fig. 4.

Fig. 6 is a detail horizontal sectional view
 45 taken substantially on line 6—6 of Fig. 5.

40 In this illustrative embodiment of the invention the well derrick is indicated at 1 and the derrick floor at 2. Arranged beneath the derrick floor is a combined rod brake and oil saver 3 mounted at the top of the well casing 4 and having suitable brake operating means 5. The 45 combined rod brake and oil saver is of the same general type as that disclosed in a co-pending application of Joseph S. Mitchell, Ser. No. 350,350, filed Mar. 27, 1929, now matured into 50 Patent No. 1,916,278, granted July 4, 1933. Ex-
 55 tends downwardly through an opening 6 in the derrick floor and through the stuffing box 7 of the oil saver is a flush jointed rod line 8. Mounted on the derrick floor above the oil 55 saver is a safety clamp 9 having slips 10 adapted

to grip the rod line to hold the rod line at certain times against downward movement within the well, this safety clamp being of the same general design as that disclosed in a co-pending application of Harry C. Johansen, Ser. No. 563- 60 597, filed September 18, 1931, now matured into Patent No. 1,924,436, granted August 29, 1933. The usual hoisting tackle of the drilling apparatus is indicated at 11 and the hook of the traveling block is indicated at 12. Connected as by 65 eyebolts 13, 13 to the derrick floor 2 are snatch blocks 14, 14. Suspended from the catline tie 15 of the catline 16 of the drilling apparatus is the improved rod line snubbing device generally designated 17, the catline tie being connected 70 within suitable eyes 18, 18 attached to the frame 19 of the snubbing device. Also connected within the eyes 20, 20 attached to the opposite ends of the snubber frame is a snubbing line 21, this snubbing line being guided by the snatch 75 blocks 14, 14 and engaging the hook 12 of the hoisting tackle in the manner shown in Fig. 1.

Now referring to the specific construction of the snubbing device 17, it will be noted that the frame 19 comprises a body 22 having rigidly attached thereto oppositely projecting I-beams 23, 23. Formed in the body 22 is a chamber 24 having mounted therein a plurality of wedge-shaped jaws or slips 25, herein four in number. These jaws are maintained in their released or 85 spread apart position by coil springs 26 interposed between the jaws as shown in Fig. 6. These jaws are each grooved at 27, and engaged in these grooves is a shifter collar 28 having trunnions 29 pivotally connected to a shifter 90 yoke 30. This yoke is pivotally connected at 31 to a bracket 32 attached to the bottom of the adjacent I-beam 23 and carries at its outer end an eye 33 to which there is connected an operating or "Jerk" line 34. Pivotally connected 95 to the trunnions 29 of the shifter collar at opposite sides of the jaw body 22 as shown in Fig. 5 are eye bolts 35 guided within perforated ears formed on the jaw body and normally held in their raised position by coil springs 36. 100 These eye bolts and springs normally maintain the jaws 25 in their upper gripping position. Secured to the shifter yoke 30 is a guide plate 37 having formed therein a slot 38 in which is guided a pin 39 carried by a pivoted latch 40. 105 This latch is pivoted at 41 on a bracket 42 attached to the bottom of the adjacent I-beam 23 of the snubbing frame. Formed at one end of the slot 38 is a notch 43, and when the shifter yoke is in its lowermost position as indicated 110

in dotted lines in Fig. 2, the pin 39 of the latch drops into the notch 43 to maintain the shifter yoke and gripping jaws in their lowermost released position. This latch may be released simply by pulling quickly downwardly on the operating line 34 to cause the pin 39 to jump out of the notch 43.

In handling a flush jointed drill rod line in and out of the drill hole while subjected to relatively high subterranean pressure, the rod brake 3 is employed for locking and holding the rod line in a fixed position so that it cannot move either upwardly or downwardly in the hole. However, owing to the more or less irregularity of the exterior surface of the rod line, the rod brake cannot be used to "ease" or slowly move the rod line out of the hole or into the hole while subjected to pressure. For instance, if the rod line were being withdrawn from the hole and there were only several hundred feet of line remaining to be withdrawn, and the pressure in the hole were relatively high, the rod line might be held in fixed position in the hole by the rod brake 3, but if it were attempted to "ease off" the brake and allow the pressure in the hole to force the rod line out, it would be necessary to release the brake sufficiently to allow the rod line to move therethrough; and if this were done, the rod line would be liable to jump upwardly for several hundred feet out of the hole before it could again be stopped. To prevent such rapid movement or jumping of the rod line, the improved snubbing device 17 is provided. Let it be assumed that the rod line is being withdrawn from the hole under high subterranean pressure and that several feet of the rod line extends above the derrick floor as shown in Fig. 1. The snubbing device is at this time suspended by the catline 16 of the drilling apparatus with the snubbing line 21 looped over the hook 12 of the hoisting tackle. The snubbing device is then lowered by paying out the catline 16, and when the snubbing device is positioned above the upper end of the rod line, the operator pulls on the operating line 34 to release the jaws 25, thereby enabling the snubbing device to be slipped down over the rod line. When the snubbing device is in the position shown in Fig. 1, the operator releases the operating line 34 and the jaws 25 then engage the rod line. The hoisting tackle is then operated and the traveling block together with the hook 12 is slowly raised until all of the slack has been removed from the snubbing line 21. The rod brake 3, which at this time has been holding the rod line in the well, is then released and the pressure in the well then forces the rod line upwardly and as a result, the jaws of the snubbing device tightly grip the rod line. The snubber is held down by the snubbing line passing over the hook on the traveling block, however, and the rod line therefore cannot move out of the hole. The hoisting hook 12 is then slowly lowered, allowing the pressure in the well to force the rod line out of the hole under the control of the snubbing device. The length of the snubbing line is such that the desired length of rod line can be "snubbed out" before the hook on the traveling block reaches the derrick floor. This may be either a single section of rod line or a double section, as desired. When the desired length of rod line has been withdrawn from the hole, the rod brake is then again set to hold the rod line against movement in the hole, and the rod sections at the upper end

of the rod line are removed and the snubbing device again connected to the upper end of the rod line, this operation being repeated until the entire length of the rod line is removed from the hole.

Conversely, if it is desired to force the rod line into the hole, this may be accomplished by slackening up on the catline 16 while the hook 12 of the traveling block is raised upwardly, thereby causing the snubbing device, together with the rod line, to be forced downwardly against the opposing subterranean pressure by power sufficiently to overcome the pressure. The jaws 25 of the snubbing device may be released at will simply by pulling on the operating line 34 to move the shifter yoke into its lowermost position, the shifter yoke being held in this position by the latch 40. The safety clamp 9 is employed for preventing downward movement of the rod line in the well when the pressure in the well suddenly drops, or for suspending the rod line in the well when the subterranean pressure is relatively low.

As a result of this invention it will be noted that an improved rod line controlling mechanism is provided whereby the rod line of an oil and gas well drilling apparatus may be moved into and out of the hole under constant control while subjected to relatively high subterranean pressure. It will further be noted that an improved rod line snubbing device is provided, of an extremely simple and rugged design and having improved operating means whereby the snubbing jaws may be operated from the derrick floor. These and other uses and advantages of the improved rod line controlling mechanism will be clearly apparent to those skilled in the art.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, the combination with a well derrick, hoisting tackle and catline, of a rod snubbing device suspended from the catline and operatively connected to the hoisting tackle whereby said snubbing device may be controlled by the hoisting tackle of the drilling apparatus, said snubbing device including rod gripping means and means operable at will for releasing said gripping means.

2. In a drilling apparatus, the combination with a well derrick, hoisting tackle and catline, of a rod line snubbing device including rod line gripping means, snatch blocks attached to the derrick floor, a snubbing line operatively connected to said gripping means and engaging said snatch blocks and also engaging the hook of the hoisting tackle whereby said snubbing device may be controlled by said hoisting tackle, and means operable independently of said snubbing line for releasing said gripping means.

3. In a drilling apparatus, the combination with a well derrick, hoisting tackle and catline, of a rod line snubbing device suspended from said catline and connected to said hoisting tackle whereby said snubbing device may be controlled by said hoisting tackle, said snubbing device having rod line gripping means, and

- means for operating said gripping means from the derrick floor.
4. In a drilling apparatus, the combination with a well derrick, hoisting tackle and catline, of a rod snubbing device suspended from the catline above the derrick floor and operatively connected to the hoisting tackle whereby said snubbing device may be controlled by the hoisting tackle of the drilling apparatus, and means operable from the derrick floor for controlling said snubbing device. 80
5. In a drilling apparatus, the combination with a well derrick, hoisting tackle and catline, of a rod snubbing device suspended from the catline above the derrick floor and including operating means operatively connected to the hoisting tackle whereby the snubbing device may be controlled by the hoisting tackle of the drilling apparatus, said snubbing device operating means including a double loop cable connection having end portions connected to the snubbing device and an intermediate portion engaging the hoisting tackle, said snubbing device also including rod gripping means and means operable independently of said cable connection for releasing said gripping means. 85
6. In a drilling apparatus, the combination with a well derrick, hoisting tackle and catline, of a rod snubbing device suspended from the catline above the derrick floor and including operating means operatively connected to the hoisting tackle whereby the snubbing device may be controlled by the hoisting tackle of the drilling apparatus, said snubbing device operating means including a double loop cable connection having end portions connected to the snubbing device and an intermediate portion engaging the hoisting tackle, and pulleys attached to the derrick floor with which said loop portions respectively cooperate, said snubbing device also including rod gripping means, and means operable independently of said cable connection for releasing said gripping means. 90
7. In a drilling apparatus, the combination with a well derrick, hoisting tackle and catline, of a rod snubbing device suspended from the catline and operatively connected to the hoisting tackle for operation thereby, said snubbing device including a frame, rod gripping means on said frame, connections on said frame adapted for engagement with the catline tie, and a double loop cable connection having engagement with connections on said frame at the outer ends thereof and having its intermediate portion engaged by the hoisting tackle, said cable connection connected to said frame independently of said gripping means. 95
8. In a drilling apparatus, the combination with a well derrick and hoisting tackle, of a rod line snubbing device connected to said hoisting tackle whereby said snubbing device may be controlled by said hoisting tackle, said snubbing device having rod line gripping means and movable with the rod line into positions a substantial distance above the derrick floor and out of the reach of an operator standing on the derrick floor, and means operable at will for operating said gripping means from the derrick floor irrespective of the position of said snubbing device with respect thereto and including an operating member extending from said snubbing device to a point within the reach of the operator. 100
9. In a drilling apparatus, the combination with a well derrick and hoisting tackle, of a rod snubbing device arranged above the derrick floor and operatively connected to the hoisting tackle whereby said snubbing device may be controlled by the hoisting tackle of the drilling apparatus, said device being engageable with a rod a substantial distance above the derrick floor and out of the reach of an operator standing on the derrick floor, and means operable at will from the derrick floor and including an operating element extending downwardly from said snubbing device to a point within the reach of the operator for controlling said snubbing device. 105
10. In a drilling apparatus, the combination with a well derrick and hoisting tackle, of a rod snubbing device operatively connected to the hoisting tackle whereby said snubbing device may be controlled by the hoisting tackle of the drilling apparatus, said snubbing device including rod gripping means, snatch blocks connected to the derrick floor, a snubbing line operatively connected to said snubbing device and engaging said snatch blocks and also engaging the hook of the hoisting tackle whereby said snubbing device may be controlled by said hoisting tackle, and means operable at will from the derrick floor for releasing said gripping means. 110
11. In a drilling apparatus, the combination with a well derrick and hoisting tackle, of a rod snubbing device arranged above the derrick floor and including operating means operatively connected to the hoisting tackle whereby the snubbing device may be controlled by the hoisting tackle of the drilling apparatus, said snubbing device operating means including a double loop connection having end portions connected to the snubbing device and an intermediate portion engaging the hoisting tackle, said snubbing device including rod gripping means, and means operable at will from the derrick floor for releasing said gripping means. 115
12. In a drilling apparatus, the combination with a well derrick and hoisting tackle, of a rod snubbing device arranged above the derrick floor and including operating means operatively connected to the hoisting tackle whereby the snubbing device may be controlled by the hoisting tackle of the drilling apparatus, said snubbing device operating means including a double loop cable connection having end portions connected to the snubbing device and an intermediate portion engaging the hoisting tackle, and pulleys attached to the derrick floor with which said loop portions respectively cooperate, said snubbing device including rod gripping means, and means operable at will from the derrick floor for releasing said gripping means. 120
13. In a drilling apparatus, the combination with a well derrick and hoisting tackle, of a rod snubbing device operatively connected to the hoisting tackle for operation thereby, said snubbing device including a frame, a rod gripping means on said frame, a double loop cable connection having engagement with connections on said frame at the outer ends thereof and having its intermediate portion engaged by the hoisting tackle, and means operable at will from the derrick floor for releasing said rod gripping means. 125
14. In a drilling apparatus, the combination with a well derrick and hoisting tackle, of a rod snubbing device operatively connected to the hoisting tackle for operation thereby, said snubbing device including a frame, rod gripping means on said frame, a double loop cable connection having engagement with connections on said frame at the outer ends thereof and having its intermediate portion engaged by the hoisting tackle, and means operable at will from the derrick floor for releasing said rod gripping means. 130
15. In a drilling apparatus, the combination with a well derrick and hoisting tackle, of a rod snubbing device operatively connected to the hoisting tackle for operation thereby, said snubbing device including a frame, rod gripping means on said frame, a double loop cable connection having engagement with connections on said frame at the outer ends thereof and having its intermediate portion engaged by the hoisting tackle, and means operable at will from the derrick floor for releasing said rod gripping means. 135
16. In a drilling apparatus, the combination with a well derrick and hoisting tackle, of a rod snubbing device operatively connected to the hoisting tackle for operation thereby, said snubbing device including a frame, rod gripping means on said frame, a double loop cable connection having engagement with connections on said frame at the outer ends thereof and having its intermediate portion engaged by the hoisting tackle, and means operable at will from the derrick floor for releasing said rod gripping means. 140
17. In a drilling apparatus, the combination with a well derrick and hoisting tackle, of a rod snubbing device operatively connected to the hoisting tackle for operation thereby, said snubbing device including a frame, rod gripping means on said frame, a double loop cable connection having engagement with connections on said frame at the outer ends thereof and having its intermediate portion engaged by the hoisting tackle, and means operable at will from the derrick floor for releasing said rod gripping means. 145

EUGENE WHINNEN.
